UNITED STATES PATENT OFFICE.

HARRY W. BEEM, OF BATAVIA, ILLINOIS.

HANGER FOR PORCH SWINGS.

Application filed March 16, 1922. Serial No. 544,211.

To all whom it may concern:

Be it known that I, HARRY W. BEEM, a citizen of the United States, and a resident of Batavia, in the county of Kane and State 5 of Illinois, have invented a new and useful Improvement in Hangers for Porch Swings, of which the following is a full, clear, and exact description.

My invention relates to improvements in 10 hangers for porch swings, and it consists in the constructions, combinations, and arrangements herein described and claimed.

An object of my invention is to provide a device of the character described for suspending a porch swing or the like, in which the "squeak" normally found in such devices 15 is entirely obviated.

A further object of my invention is to provide a device of the character described 20 for suspending a porch swing or the like on an anti-friction bearing to permit a free oscillatory movement of the swing.

A further object of my invention is to provide a device of the character described 25 in which the rocker bearing support may be locked in adjustable position in alinement with the porch ceiling hooks and the grap- ple hooks on the swing.

A further object of my invention is to 30 provide a device of the character described which is cheap to manufacture and which is thoroughly practical for the purpose in- tended.

Other objects and advantages will appear 35 in the following specification, and the novel features of the invention will be particu- larly pointed out in the appended claims.

My invention is illustrated in the accom- 40 panying drawings, forming part of this ap- plication, in which—

Fig. 1 is a front elevation of my hanger for porch swings,

Fig. 2 is a sectional view along the line 2—2 of Fig. 1,

Fig. 3 is a front elevation of a portion of 45 the oscillating support showing the retaining bolt.

In carrying out my invention, I make use 50 of ceiling hooks 1, which are secured to the ceiling of a porch or the like and from which the swing or hammock is normally sus- pended by directly connecting the support- ing chains thereto.

In the present form of my invention, I provide a clamp member which consists of a 55 stationary jaw 2 having a bolt 3 passed therethrough transverse to the outer surface 4 thereof. A movable jaw 5 of metal plate is disposed in front of the surface 4 of the jaw 2 and may be drawn into close engage- 60 ment with the hook 1 by means of a nut 6, which is turned upon the bolt 3. The hook 1 is passed beneath the bolt 3, as shown in dotted lines in Fig. 1. The lower portion of the stationary jaw 2 is formed in a sleeve 7 65 having a bore extending transverse to the bolt 3. A relatively long bolt 8 is passed through the sleeve 7 and serves as a means for pivotally supporting a metal bearing support member 9, substantially as shown in 70 Fig. 1. The support member 9 is provided with a pair of spaced apart sleeve portions 10, which sleeve portions are arranged to receive the bolt 8. A nut 11 is provided for the bolt 8 by means of which the support 75 member 9 may be securely set in any of its pivotally adjusted positions relative to the sleeve 7.

The support member 9 is provided at its lower extremity with a hard steel bearing 80 plate 12 riveted thereto by means of rivets 13. The upper bearing surface 14 of the plate 12 is in a plane parallel to the bolt 8.

The support member 9 is provided with a pair of shallow flat bosses 15, through which 85 the rivets 13 extend and upon which the plate 12 is disposed. The inner walls 15' of the bosses 15 are inclined substantially as shown in Fig. 1 to permit the oscillatory movement of an oscillating supporting strap 90 16 hereinafter described, the depth of the bosses 15 being of sufficient depth to permit the introduction of the oscillating strap 16.

The boss 17 is provided on the rear sur- 95 face 18 of the support member 9 and has a bore 19 extending axially therethrough. The inner surface 20 of the support member 9 is provided with a relatively shallow boss 21, which provides a means for establishing a 100 clearance between the oscillating strap 16 and the surface 20 thus obviating undue friction. The bore 19 is disposed so that its axis is exactly in registration with a point on the upper bearing surface 14 of the steel plate 12. A retaining shaft 22 having a 105

head 23 is disposed in the bore 19 so that its head 23 is flush with the outer surface of the boss 17 and its opposite end is in contact with the inner surface of the plate 12. A 5 lock pin 24 is provided in the boss 17 and serves as a means for preventing the longitudinal movement of the shaft 22.

Means for supporting the oscillating strap 16 for oscillatory movement is provided in 10 an elongated opening 25 through the strap 16, as shown in Figures 2 and 3. The shaft 22 is passed through the opening 25 and thus prevents the lateral shifting of the strap 16 relative to the supporting member 9. The upper end of the strap 16 is bent over in a substantially U-shaped manner, as shown at 26 and a hard triangular steel bearing member 27 is disposed intermediate the adjacent walls of the U-shaped portion of 15 the strap 16. The lower end of the bearing member 27 is arcuate in shape, as shown in 20 28, and is arranged to bear directly upon the surface 14 of the bearing plate 12. The rivet 29 provides means for securing the bearing member 27 against movement relative to the strap 16. It should be noted that as the bearing member 27 rests upon the surface 14 of the plate 12, that there is a clearance above and below the shaft 22 and the 25 strap 16 provided by the elongated opening 25.

Means for suspending a porch swing or the like from the strap 16 is provided in 30 cross bolts 30, from which a chain 31 is suspended. The lower link of the chain 31, as shown at 32, is arranged to receive a grapple hook 33 of a swing, as partially shown in dotted lines at 34.

From the foregoing description of the 40 various parts of the device, the operation thereof may be readily understood. My hanger for porch swings may be quickly and easily attached for use to the ordinary hooks secured to the ceiling of a porch or the like, 45 as shown at 1 in the manner described. My present invention provides for a means which may be adapted to swings of various lengths in the following manner. Let us assume that the hooks 1 for suspending the 50 swing are approximately ten feet apart and that the length of the swing 34 is only six feet. It is obvious that the chains 31 would be disposed at an angle from the vertical.

In fixing my clamping jaws 2 and 5 to 55 the hook 1, I first make sure that the jaws 2 and 5 are disposed in a plane parallel to the oscillatory path of the swing. I thereupon loosen the nut 11, and the bearing member 9 will move upon the bolt 8 until 60 a line drawn from the bolt 8 to the grapple hook 33 will include the bearing 9, the strap 16 and the chains 31. The nut 11 is then tightened, which secures the bearing member 9 in its adjusted position and in 65 assuming this position the thrust upon the

strap 16 will be entirely borne by the bearing member 27 in contact with the plate 12. The swing is now ready for use. As the swing is oscillated, the arcuate surface 28 of the bearing 27 will make rolling contact, 70 thus providing an anti-friction bearing for the oscillating strap 16.

I claim:

1. In a device of the character described, a metal bearing plate having a flat upper 75 edge, a rocker bearing member arranged to bear on the flat upper edge of said bearing plate, a load supporting strap connected to said rocker bearing member, and means for preventing lateral movement of said rocker member other than the oscillatory movement thereof, said means comprising a pin fixed in perpendicular relation to said bearing member and having its axis in the plane of the flat upper edge of said bearing member, 80 said pin arranged to engage said rocker bearing member.

2. A device of the character described comprising a bearing plate having a substantially flat upper surface, means for supporting said bearing plate in a horizontal plane, a rocker bearing member adapted to bear on the flat upper surface of said bearing plate and a load supporting strap rigidly connecting to said rocker bearing and extending downwardly therefrom, and means for preventing lateral movement of said strap other than the oscillating movement thereof. 95

3. A device of the character described 100 comprising a bearing plate having a substantially flat upper surface, means for supporting said bearing plate in a horizontal plane, a rocker bearing member adapted to bear on the flat upper surface of said bearing 105 plate and a load supporting strap rigidly connected to said rocker bearing member and extending downwardly therefrom, whereby said strap may oscillate with the point of contact of said rocker bearing and said bearing plate as a center, and a shaft disposed through said strap transverse thereto on an axis in common with the said point of contact of said rocker bearing and said bearing plate for preventing lateral movement 110 of said strap relative to said bearing plate. 115

4. A device of the character described comprising a clamping member adapted to engage a ceiling hook or the like, a bearing supporting member hingedly mounted on said clamping member, a hard metal bearing plate having a flat upper surface mounted on said bearing supporting member, a rocker bearing adapted to bear on the flat upper surface of said bearing plate and a load supporting strap rigidly connected to said rocker bearing and extending downwardly therefrom. 120 125

5. A device of the character described 130

comprising a clamping member adapted to engage a ceiling hook or the like, a bearing supporting member hingedly mounted on said clamping member, a hard metal bearing plate having a flat upper surface mounted on said bearing supporting member, a rocker bearing adapted to bear on the flat

upper surface of said bearing plate and a load supporting strap rigidly connected to said rocker bearing and extending downwardly therefrom, and means for preventing lateral movement of said strap other than the oscillating movement thereof.

HARRY W. BEEM.
